UNITED STATES PATENT OFFICE.

HERMAN L. FEHLBERG, OF LA CROSSE, WISCONSIN.

MACHINE FOR PACKING SHINGLES AUTOMATICALLY.

SPECIFICATION forming part of Letters Patent No. 424,673, dated April 1, 1890.

Application filed August 2, 1887. Serial No. 245,989. (No model.)

To all whom it may concern:

Be it known that I, HERMAN L. FEHLBERG, a citizen of the United States, residing at La Crosse, La Crosse county, State of Wisconsin, have invented a new and useful Machine for Automatically Packing Shingles; and I do declare the following to be a full, clear, and exact description of the invention, such as will enable others skilled in the art to which it appertains to make and to use the same, reference being had to the accompanying drawings, forming a part of this specification, and to letters of reference marked thereon.

This invention relates to that class of machines which pack shingles as they are fed in, (after being jointed,) it being easy to manipulate and perfectly automatic in operation.

The object of this invention is to save the time and labor usually spent in packing shingles by hand, which object I have attained by the means illustrated in the accompanying drawings.

Figure 1 is a sectional view of my machine on the line A A of Fig. 3. Fig. 2 is a similar view taken on the line B B of Fig. 3. Fig. 3 is a side elevation of the machine. Fig. 4 is a top plan view. Fig. 5 is an elevation of the side opposite that shown in Fig. 3. Fig. 6 is a detail view of the shaft G and clutch thereon, and Fig. 7 is a sectional view taken on the line C C of Fig. 3.

Similar letters refer to similar parts throughout the several figures.

Referring to the drawings, E indicates the main driving-shaft, Fig. 3, and upon said shaft there is mounted a worm-gear E', pulleys S² and S³, and friction-wheel F. The wheel F is thrown in and out of contact with F' by a lever working in L, for a purpose hereinafter named. Worm-gear E', Fig. 7, drives shafts P P' P² P³ and also clutches H and U. The clutches H and U are loose on shafts G and O and revolve freely on same. The shafts O and G have slots J², as shown in Fig. 7, in which a key works, as shown in Fig. 6. I have given the side section in Fig. 6, and in Fig. 7 the top section of slot, key, and lug of shafts G and O. The said keys, on which clutches H' and U² are fastened, have lugs on one side, as shown in Fig. 6 at L². Collars L⁴ and U⁷ are made to bear on these lugs by

springs K³ and U⁶, which are kept tight by the cams K and O'. The collars L³ and U⁵ are fastened to shafts O and G. When lever K', Figs. 2 and 3, is disengaged from between lug L² and collar U⁵, spring U⁶ will force clutch U² in gear, and shaft O will make one turn, when lever K', having dropped back, will throw clutch U² out, and shaft O will stop. Shaft G, Fig. 6, works on the same principle, collar L³ keeping clutch H in place. The clutch U on shaft O is held in place by sleeve J⁵, Fig. 7, and collars J³ and J⁴. Sleeve J⁵ has a set-key, on which works clutch U', being thrown in and out of gear by a lever L⁷. On sleeve J⁵ is fastened a gear U³, which drives shafts U⁴, on which is fastened rolls S, carrying belts S⁴ and S⁵, Fig. 4.

Belts S⁵, Fig. 4, have cleats fastened on at suitable distances for carrying shingles out of feed-boxes M' and M², Fig. 3, where they are to be piled in butt-end toward the outside of machine, as shown in Fig. 2. These boxes have an opening on the side at the bottom toward the way belts S⁵ travel, which is a little larger than the size of shingles, thus allowing cleats on belts S⁵ to carry shingles through this opening single. Said shingles are then deposited on belts S⁴, which carry them along and shove them on fly T², for a purpose hereinafter described.

The saw-frame Q, Fig. 2, is moved back and forth by crank J, which is fastened on shaft G and is held in place by guides Q' and Q². Saw S' is run by pulley S² and belt, as shown, through tightener R and cord R', slack being taken up by weight R² when saw-frame Q passes back and forth. The saw-frame Q and shaft G are under control of lever L² Z; but when said lever is lifted from between collar L³ and lug L² shaft G will make one turn, thus working saw-frame Q back and forth once, when said frame Q will stop on left-hand side of machine.

The wheel V, fastened on shaft G and having a notch cut out, as shown in Fig. 7, works on lever V', which in turn works arm V³ through rod V². Arm V³ is fastened on a shaft, which works arms V⁴ up and down through bevel-gears, as shown, for a purpose hereinafter named.

The fly T² is hollow and connected by trunk

T' to fan X , driven by pulley S^3 , which creates a suction, and this hold shingles on fly T^2 while being deposited on car T^5 . The fly-shaft T is worked by pinion O^4 and segment 5 O^3 , being connected by rod, as shown, to crank O^2 , fastened on shaft O . The segment O' is also fastened on shaft O and works lever N , which works N^3 , geared into N^4 on shaft W^3 , on which is pulley W , working-valve W' , and 10 spring W^2 . This spring shuts suction off when fly T^2 is on the point of returning, and thus causing shingles on fly T^2 to be deposited on car T^5 . The shaft O^3 is driven by shaft T , Fig. 1. Friction-pulley F' , with chain-wheel 15 and clutch, as shown, revolves freely on said shaft O^3 . Clutch O^5 is held by set-key on and revolves with shaft O^3 and can be thrown out of gear from F' by lever L' . The chain O^6 , Fig. 3, drives the wheels, which have 20 threads cut inside and work on O^7 , running car and table T^5 up and down. When F' is driven by F and clutch O^5 is lifted out of gear by lever L' , table and car T^5 will be caused to run up by chain O^6 , Fig. 3; but 25 when F is thrown out and O^5 dropped in gear table and car T^5 will be caused to run down the thickness of a shingle at each half-turn of shaft O^3 , for a purpose hereinafter named.

T' is a stop on fly, the distance between this 30 and saw S' being the exact width and the distance between guides Z' and Z^2 being the exact length of a bundle of shingles. Rollers S , Fig. 2, have enough difference in their diameter so that one row of shingles may pass 35 over the other, and thus secure the lap necessary in bunching shingles.

Z Z are shingles.

Bar T^6 , Fig. 5, is for V^4 to rest on when holding down shingles while saw S' is cutting off 40 the width on fly T^2 .

I is the driving-pulley.

The operation of the above-described devices constituting my shingle-packer is as follows: Assuming that the driving-shaft E is in motion and that shingles have been piled in feed-boxes M' and M^2 , thick end toward the outside of machine, and that car and table T^5 have been run up to the proper height, by raising clutch O^5 out of gear from F' and forcing 45 friction-wheel F on F' will raise car and table T^5 through chain O^6 and screws O^7 , and when high enough throw out friction F from F' and drop back clutch O^5 . By setting clutch U' in gear with clutch U starts sleeve J^5 , and through 50 chain runs rolls S , on which travel belts S^4 and S^5 . Belts S^5 have cleats, as shown in Figs. 4 and 5, which take along shingles one at a time from bottom of feed-boxes M' and M^2 and deliver said shingles on belts S^4 , which 55 carries same along and pushes them on fly T^2 until they strike stop T' on fly, when rolls S must be thrown out of gear again by lever L^7 . By lifting lever L^2 saw S' will be started across and cut off the exact width of the bundle of shingles. Just before saw S' gets to 60 cutting arms V^4 will be caused to come down on the shingles by wheel V , lever V' , rod V^2 ,

and crank V^3 , as shown. Arms V^4 will hold the shingles on bar T^6 and fly T^2 while saw S' is passing from side to side. When saw S' arrives at the left-hand side, Fig. 2, lever L^2 Z will throw shaft G out of gear again. Wheel V , having a notch cut out, as shown, will allow spring M to pull up arms V^4 after shaft G has made one turn. Collar K , with lug 70 having lifted lever K' , disengages clutch U^2 , which allows shaft O to make one turn. Crank O^2 , being fastened on shaft O , will make fly-shaft T turn half-way over and back through segments O^3 O^4 and rod, as shown, shingles 75 being held on by suction created by fan X , air passing in at openings T^3 on fly T^2 , but covered by shingles when fly T^2 is loaded. Ribs T^4 on fly T^2 are to support shingles while being carried over and disposed of on car T^5 . 80 When fly T^2 is returning, the cam O' on shaft O having opened valve W' through lever N , gears N^3 N^4 , shaft W^3 , with pulley W , will let lever N go and spring W^2 will shut suction off, thus causing fly T^2 to deposit shingles on 85 car T^5 the instant it starts to return. When fly T^2 is returning, bevel-gears on shaft T and O^3 will cause clutch O^5 to turn F' far enough so that car and table T^5 will be lowered the thickness of a shingle, thus making room for next 90 layer, and so on. When a certain number of layers are deposited, car T^5 is pushed off and the table on which the track lies is raised again and another is pushed on.

Having thus described my invention, what 100 I claim as new, and desire to secure by Letters Patent, is—

1. In a machine for packing shingles, the combination, with a main driving-shaft, of a friction-wheel mounted thereon and adapted 105 to engage a friction-wheel mounted on the lower end of a vertical shaft F' , a sprocket-wheel secured to said shaft, and a clutch mechanism connecting said shaft with the shaft O^8 , said shaft O^8 being revolved by the shingle-feeding mechanism, the vertical threaded rods O^7 , supporting the car T^5 , toothed nuts upon each of the threaded rods, and a chain 110 O^6 , passing around said nuts and the sprocket-wheel on the shaft F , whereby the car is either 115 raised or lowered as the sprocket-wheel is driven by main shaft E or shaft O^8 , as and for the purpose described.

2. In a machine for packing shingles, the combination, with the fly T^2 , adapted to receive the shingles, of the air-trunk T' , connected therewith, and a fan for producing a suction, the valve W' , for controlling the suction, and a spring W^2 and the shaft W^3 , adapted to operate the valve, shaft O , geared with the shaft W^3 , and connections between the said shaft O and shaft T , all arranged and adapted to operate substantially as shown and described.

3. In a machine for packing shingles, the combination, with the shaft T , of the fly T^2 , secured thereon, pinion O^4 , mounted upon said shaft, and the toothed segment O^3 , adapted for engagement with the said pinion, the

shaft O, crank O², connected therewith, and the shaft connecting the said crank and segment O³.

4. In a machine for packing shingles, the combination, with the shaft G, of the cam-wheel V, mounted upon one end of said shaft, the crank-arm J, secured upon the shaft at the opposite end and operating the saw-carrier frame, the lever V', link-arm V², lever V³, arms V⁴, and the shafts and gears connecting said lever and arms, whereby the arms V⁴ are raised and lowered, substantially as and for the purposes described.

5. In a machine for packing shingles, the combination, with the shaft G, of the crank-arm J, secured to its inner end, the saw-frame Q, connected to the crank-arm and adapted to be moved across the frame by means of the same, a cam-wheel secured to the outer end of the shaft G and operating a series of levers to raise and lower the arm V⁴, the fly T², upon which the shingles rest while being sawed, a clutch H' upon the shaft G, and a lever controlling the same, substantially as and for the purpose set forth.

6. In a machine for packing shingles, the combination, with the main driving-shaft E, of the shaft G, connected therewith by means of shafts P and P' and gears attached

thereto, the shaft O, connected with main shaft E by means of shafts P and P' and gears attached thereto, the gear V and clutch for operating the same, crank-arm O², secured to one end of the shaft O, the segment O³ and rod connecting the said segment and crank-arm, the shaft T, and pinion O⁴ upon the end thereof, adapted to engage the segment O³, the fly T², mounted upon the shaft T, a trunk T', connected with the said fly, the fan X and valve W', the belts S⁴ and S⁵, driven in the same direction by the shafts U¹, connected with the sprocket-wheel U³ upon the end of the shaft O, the feed-boxes M and M², arranged at the forward end of the machine and over the belts S⁵, the saw-frame Q, operated by the crank-arm J on the shaft G, the saw S', driven by belts from the pulley S² upon the main shaft E, the tightener R, to take up slack in belt, the cord R', and weight R² for operating said tightener, all of the above-mentioned parts being combined and adapted to operate substantially as shown and described.

HERM. L. FEHLBERG.
